CLAIM

The ornamental design for a 3D modulator for a projector, as shown and described.

DESCRIPTION

FIG. 1 is a perspective view of a 3D modulator for a projector which embodies my new and original design; FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view thereof showing retraction of the 3D modulator; and,

FIG. 9 is a top plan view thereof showing the 3D modulator positioned operatively adjacent a projector.

The broken line showing the projector in FIG. 9 is for the purpose of illustrating environmental structure and forms no part of the claimed design.
